UNITED STATES PATENT OFFICE.

ROBERT JAMES EAST, OF WINNIPEG, MANITOBA, CANADA.

DRINKING-FOUNTAIN HEAD.

1,272,927.

Specification of Letters Patent.

Patented July 16, 1918.

Application filed November 21, 1917. Serial No. 203,161.

To all whom it may concern:

Be it known that I, ROBERT JAMES EAST, of the city of Winnipeg, in the Province of Manitoba, Canada, have invented certain new and useful Improvements in Drinking Fountain Heads, of which the following is the specification.

The invention relates to improvements in drinking fountain heads, particularly as utilized in public places and the principal object of the invention is to provide a sanitary drinking head which will throw a constant stream regardless of the fluctuation of the pressure of the water supply pipe, the thrown stream being directly controlled by an entrapped head of water operating under the force of gravity.

A further object of the invention is to provide a head which delivers the stream to the side whereby the water after falling from the lips or mouth of one drinking does not again come in contact with the head but falls into the basin.

A further object of the invention is to provide the head with a detachable mouth ring which will prevent the lips from contacting with the head and which will allow of the ring being removed and disinfected from time to time.

A still further object of the invention is to provide a drinking head which can be readily converted from a valve controlled type to a constant stream type.

With the above more important objects in view the invention consists essentially in the arrangement and construction of parts hereinafter more particularly described and later pointed out in the appended claims, reference being had to the accompanying drawing in which:

Figure 1 represents a front view of the appliance as set up in a bowl.

Fig. 2 represents an enlarged detailed longitudinal sectional view centrally through the head.

Fig. 3 represents a side view of a part of the head.

Fig. 4 represents a horizontal sectional view through the head, the section being taken in the plane denoted by the line X—X' and looking downwardly.

Fig. 5 represents a horizontal sectional view through the upper end of the stand pipe, the section passing through the slot therein.

Fig. 6 represents a horizontal sectional view through the admission tube.

Fig. 7 represents a vertical sectional view centrally through the appliance showing the construction modified to provide a head of 60 the constant stream type.

In the drawing like characters of reference indicate corresponding parts in the several figures.

1 represents the usual draining bowl or 65 catch basin usually employed in private and public places where a drinking fountain is installed.

Such a bowl presents a feed pipe 2 connected with a water main and a drain pipe 70 3 leading from the bowl. The pipe 2 customarily terminates centrally of the interior of the bowl and to this pipe the fountain head is attached.

Where my fountain head is employed I 75 connect a T-elbow 4 to the upper end of the pipe 2 and to the T-head I secure a short length of horizontally disposed pipe 5 fitted with an upturned elbow 6 which carries the head. The T-elbow is fitted with a controlling valve 7 which can be regulated as desired and which can be reached by a suitable tool after the inclosing cap 8 has been removed.

The pipe 5 is of such a length that when 85 the head is attached to the elbow it takes a position more or less to the side of the bowl. The head comprises the following parts:

9 represents an upper cylindrical casing having the upper end thereof closed by a 90 suitably shaped screw cap 11 and the lower end thereof closed and provided with outlet drain holes 10 and carrying an extension 13 forming a valve chamber. The lower end of the extension is screw threaded as shown 95 at 14 on to the upturned end of the elbow 6 so that the head takes an upright position in respect to the bowl.

15 represents a stand pipe having the lower end thereof secured in any suitable 100 manner permanently to the inner end of the valve casing and the upper end thereof closed as indicated at 16 and terminating within the cap 11. The lower end of the stand pipe is contracted to provide a valve 105 seat 17 while the upper end is fitted with an overflow opening or slot 18.

19 represents an admission tube which in the valve controlled type of head takes the form of a valve stem, the upper end of which 110 passes slidably through the end 16 of the stand pipe and slidably through a boss 20 carried by the head while the lower end passes slidably through the lower end of

the stand pipe and is fitted with a valve 21 adapted to close upwardly on the seat 17.

The upper end of the stem is fitted with a finger or thumb knob 22 for manipulating 5 the valve and a spiral spring 23 is inserted between the knob and the boss which spring has a natural tendency to force the stem up and normally hold the valve closed.

The stem is bored longitudinally at 24 to 10 provide an admission duct having the inlet end 25 opening to the side of the stem in a location adjacent the valve and the upper end opening to the side of the stem at 26 in a location somewhat below the slot 18. From 15 this arrangement it will be obvious that when the valve is closed no water can enter the duct from the valve chamber through the opening 25 but that upon the valve being unseated the opening 25 communicates with 20 the interior of the valve chamber and allows of a flow from the valve chamber through the duct and into the stand pipe through the opening 26.

27 represents an upwardly inclined side 25 nozzle communicating with the lower end of the stand pipe and adapted to eject a stream of water through a suitable slot or side opening 28 formed in the side of the casing 9.

29 represents a mouth ring which is oval 30 in shape and of such a size that it will completely surround the mouth clear of the lips. This ring is placed in an upright position and positioned so that the stream discharged through the opening 28 from the 35 nozzle will pass more or less centrally through the ring. The ring is spaced from the casing by upper and lower legs 30 and 31 and is detachably secured to the same in any suitable way such as by a pair of side legs 40 32 and 33, one of which is supplied with a key-hole slot 34 receiving a headed pin 35 attached to the casing 9 and the other of which is secured such as by a screw 36 to the casing.

45 From this latter arrangement it will be obvious that the ring can be removed and disinfected from time to time by simply undoing the screw 36 and then sliding the ring latterly to allow the head of the pin 35 to 50 escape from the large end of the key-hole slot.

Considering this appliance set up as shown and the valve 7 regulated as is customary to control the stream of water through the pipe 55 2 from the mains, the operation is as follows:—

When one wishes to drink, the knob 22 is 60 pressed down by the thumb and the one drinking bends down so that his mouth is opposite the ring. The instant the thumb knob is pressed down the valve is unseated with the result that water flows into the stand pipe in the manner herein before disclosed and discharges through the opening 65 28 from the nozzle 27 so that the one drink-

ing can drink from the running stream adjacent the ring.

According to this arrangement it will be obvious that the stream through the nozzle is discharged by the force of gravity acting 70 on the head of water in the stand pipe and is in no way dependent on the pressure in the water main.

I desire, when installing this appliance, 75 that the valve 7 be set so that under normal pressure in the main and with the nozzle discharging to full capacity the head of water in the stand pipe will be approximately equal to the height of the lower edge of the slot 18. With such a setting the stream delivered from the nozzle will not vary the slightest either in the distance which it is thrown or in amount as under this set condition the pressure acting is that due to the 80 head of water in the stand pipe and is entirely independent of the fluctuation in pressure at the main.

Should the pressure in the main increase 85 above normal the stream is not affected in any way as an increase in the pressure in the main will simply cause the water to overflow through the slot 18 in the stand pipe where it falls and escapes to the bowl through the openings 10.

Obviously the instant the knob is 90 released the valve seats and closes off the supply. When this occurs there will be water trapped in the stand pipe to the height of the nozzle, which water will prevent accumulated dust, etc., from entering the stand 95 pipe by way of the nozzle.

A feature which I wish to point out is that owing to the fact that the nozzle is inclined there is no possibility of the water falling from the lips and mouth of the one 105 drinking dropping back on to the head as occurs in the vertical discharging nozzles now on the market. Accordingly the appliance, in this regard, is most sanitary.

Further, owing to the constancy of the 110 stream discharged there is no disagreeable spattering of the water on the face of the one drinking as he can readily regulate his mouth to the stream which does not vary.

Further, owing to the above fact it is 115 entirely unnecessary for the one drinking to even place his mouth against the guard ring.

In Fig. 7 of the drawing I have shown the device in a modified form with the valve removed. In this construction the admission tube, instead of being a valve stem, is a 120 stationary member secured to the lower end of the stand pipe.

The duct 24 opens directly to the interior 125 of the extension 13. With this form of construction the stream thrown from the nozzle is directly under the control of the head of water in the stand pipe and is a constant one as by omitting the valve there is a constant flow from the main.

What I claim as my invention is:—

1. A drinking fountain head connected directly with a water supply pipe of variable pressure and constructed to discharge a stream of water expelled by the force of gravity.
  2. A drinking fountain head connected with a water supply pipe of variable pressure and constructed to deliver a constant stream of water expelled by the force of gravity acting upon a constant head of water maintained within the drinking head.
  3. A drinking fountain head having an inlet water passage, an outlet nozzle and an intervening water chamber surrounding the inlet water passage and communicating therewith and with the outlet nozzle and with the entrance end of the passage to the chamber elevated above the nozzle whereby a head of water can be maintained within the chamber.
  4. The combination with a feed water supply pipe, of an inlet water tube communicating with the feed pipe, a stand pipe spaced from and receiving the tube and having an opening in the upper end thereof and a discharging nozzle located at the lower end of the stand pipe, the said inlet passage opening to the interior of the stand pipe in a location above the discharge nozzle.
  5. The combination with a feed water supply pipe, of a water inlet tube communicating with the supply pipe and having an outlet opening in the upper end thereof, a stand pipe spaced from and receiving the tube and having the ends thereof closed and an opening in the side thereof toward the top and above the aforesaid opening and a discharge nozzle communicating with the lower end of the stand pipe and located beneath the outlet opening.
  6. The combination with a feed water supply pipe, of a stand pipe connected with the water supply pipe and having the upper end thereof closed and the lower end thereof presenting a valve seat and provided adjoining the upper end with an overflow opening, an inlet tube slidably mounted in the stand pipe and spaced therefrom to provide a water chamber, a valve secured to the lower end of the inlet pipe, means normally retaining the valve closed against the seat, a passage in the tube having the lower end opening to the side of the tube in a location above the valve and the upper end opening to the water chamber in a location adjacent the overflow opening and a latterly discharging nozzle secured to the lower end of the stand pipe.
  7. The combination with a feed water
- supply pipe, of a stand pipe connected with the supply pipe and having the upper end thereof presenting an overflow opening and the lower end a valve seat, a valve stem slidably mounted in the stand pipe and spaced therefrom to provide a water chamber, a valve secured to the lower end of the stem, means normally retaining the valve closed against the seat, an inlet passage in the stem having the lower end opening to the side of the stem in a location adjacent the valve and the upper end opening to the water chamber in a location adjacent the overflow from the stand pipe, a knob secured to the stem for manipulating the valve and a latterly discharging upwardly inclined nozzle secured to the lower end of the stand pipe and opening to the water chamber.
8. The combination with a feed water supply pipe, of a stand pipe connected with the supply pipe and having the upper end thereof presenting an overflow opening and the lower end a valve seat, a valve stem slidably mounted in the stand pipe and spaced therefrom to provide a water chamber, a valve secured to the lower end of the stem, means normally retaining the valve closed against the seat, an inlet passage in the stem having the lower end opening to the side of the stem in a location adjacent the valve and the upper end opening to the water chamber in a location adjacent the overflow from the stand pipe, a latterly discharging upwardly inclined nozzle secured to the lower end of the stand pipe and opening to the water chamber.
9. The combination with a drinking fountain head constructed to discharge a laterally directed stream, a casing surrounding said drinking head and a guard ring on said casing and in a location such that the stream of water is expelled therethrough, the said guard ring being spaced from the casing by means of upper and lower legs and detachably secured to the same by a pair of said legs, one of which is provided with a key-hole slot adapted to receive a headed pin on the casing and the other being secured to the casing by a screw, substantially as described.

Signed at Winnipeg, this 22nd day of October, 1917.

ROBERT JAMES EAST.
